United States Patent Office

Des. 215,829
Patented Nov. 4, 1969

215,829

BUILDING

Jack W. Beck, Blue Springs, Mo., assignor to Plasto
Incorporated, Mission, Kans., a corporation of Kansas

Filed Nov. 25, 1968, Ser. No. 14,620

Term of patent 14 years

Int. Cl. D25—04

U.S. Cl. D13—1

Fig. 1.

Fig. 2.

Fig.3.

Fig.4.

FIG. 1 is a front elevational view of a building, showing my new design;

FIG. 2 is a top plan view thereof;

FIG. 3 is a side elevational view of one side of the building, with the opposite side thereof being of similar configuration; and

FIG. 4 is a rear elevational view of the building.
I claim:

The ornamental design for a building, as shown and described.
